VENDING MACHINE

Philip Cedar, Cleveland, Ohio

Application April 3, 1933, Serial No. 664,232

2 Claims. (Cl. 312—83)

This invention relates to vending machines, and has more particular reference to an improved machine for vending elongated articles such as cigarettes, cigars, and the like.

5 The primary object of the present invention is to provide a vending machine of the above kind having novel coin-controlled article-dispensing means which is extremely simple in construction, efficient in operation, and unlikely to readily get 10 out of working order.

More particularly, the present invention contemplates the provision of a vending machine wherein the articles to be dispensed are fed one at a time between a pair of gates in position to be 15 dispensed, one of the gates being yieldably urged toward the other to retain the lowermost article, and wherein means engageable by the coin in a manually operable coin slide is provided to move the movable gate away from the cooperating gate 20 to effect discharge of the lowermost article from the machine.

The invention further contemplates provision of means for promptly and positively discharging the coin from the coin slide as soon as the lowermost article is released by the gates so that the movable gate may be instantaneously returned toward the cooperating gate member for engaging and supporting the next succeeding article in position to be dispensed when the coin slide is again 30 operated.

Other objects and features of the invention will become apparent from the following description when considered in connection with the accompanying drawings, in which:

35 Figure 1 is a front elevational view of a vending machine embodying the present invention.

Figure 2 is an enlarged vertical section on line 2—2 of Figure 1.

Figure 3 is an enlarged vertical section on line 3—3 of Figure 1.

40 Figure 4 is a view partly in vertical section and partly in elevation with the plane of section at right angles to that of Figure 2; and

Figure 5 is a horizontal section on line 5—5 of Figure 4.

45 Referring in detail to the drawings, the present vending machine includes a suitable casing 5 with in and adjacent one side of which is mounted a hopper or magazine 6 adapted to contain the articles to be dispensed or vended. The hopper 6 extends from the top of the casing 5 to a point spaced above the bottom of the latter as shown clearly in Figures 2, 3 and 4, and the front and rear walls of said hopper converge in a downward direction to provide a bottom discharge opening

1 slightly longer and slightly wider than the elongated articles 8 to be dispensed. The articles 8 are placed horizontally in superposed relation within the hopper 6 and are shown for example as consisting of cigarettes adapted to be vended singly. The casing 5 is provided with a hinged or openable cover 9 so that access may be had to the top of hopper 6 for replenishing the supply of articles to be vended from time to time. Suitable means, not shown, will of course be provided 10 for locking the cover 9 closed to prevent unauthorized access to the interior of the casing.

The hopper 6 is sustained by a horizontal plate 10 mounted within the casing 5 and having a slot conforming in size and shape to that of the discharge opening 7 of the hopper 6 and registered with said discharge opening 7. Obviously, the plate 10 may be constituted by integral extensions of the front and rear walls of hopper 6 as shown. Arranged in spaced relation to and below the plate 20

10 is another plate 11 having a discharge opening 12 arranged in vertical alinement with the discharge opening 7 of hopper 6 to permit the article 8 to pass therethrough when released by the coin-controlled means to be presently described. An 25 inclined chute 13 is arranged below the plate 11 onto which the articles fall as they are dispensed and by means of which they may be directed outwardly and downwardly to a point exteriorly of the casing for delivery to the customer. The 30

front wall of the casing 5 is provided with a slot or opening 14 through which the articles are discharged by passing down the chute 13, and the latter is formed exteriorly of the casing or directly 35 in front of the slot or opening 14 with a trough or tray 15 into which the articles are ultimately delivered in position to be conveniently removed by the customer. Upstanding and diverging flanges 16 may be provided at the front and rear of the slot 12 of plate 11 to positively direct the 40

articles to said slot 12 onto the chute 13 as they are dispensed from the hopper 6. As shown, the lower plate 11 may be supported by and spaced from the plate 10 through the medium of bolts 17 and spacing sleeves 18 respectively passing 45 through and arranged between said plates 10 and 11, the sleeves 18 being provided on the bolts 11 as shown in Figure 2.

The coin-controlled means for dispensing the articles includes a pair of gates 19 and 20 mounted 50 on the under side of the upper plate 10 respectively at the front and rear sides of discharge opening 7 of hopper 6 and between which the articles 8 are adapted to be successively fed by gravity one at a time to be supported in po- 55

sition to be dispensed. As shown, the gate 19 is mounted in a fixed position although adjustably hinged so that it may be set in the proper relation to gate 20 in accordance with the size and nature of the articles to be dispensed. For this reason, the gate 19 is hingedly mounted on a pivot pin 21 and has a barrel carrying a set screw 22 adapted to impinge against the pivot pin 21 to secure the gate 19 in adjusted position.

10 The gate 20 is hinged as at 23 for free swinging movement about a horizontal axis toward and from the gate 19, said gate 20 depending from a hinged barrel integral therewith and having its said hinged barrel extended to one side of the hopper as indicated at 24 in Figure 5. The hinged barrel extension 24 of swinging gate 20 is provided with a rigid depending arm 25, and rigid with and extending forwardly from the intermediate portion of arm 25 is a second arm 26 to

15 which is attached one end of a helical tension spring 27 having its other end attached to the plate 10 so that said spring normally acts to swing the gate 20 toward the gate 19 so that the lowermost article 8 is received between and supported by said gates in position to be dispensed. Movement of gate 20 toward gate 19 is properly limited by any suitable means such as a cross piece 28 provided intermediate the ends of an elongated slot 29 provided in a further plate 30

20 mounted in the casing 5 in spaced relation to and above the plate 11. The arm 25 depends through and works freely in the rear portion of slot 29, and also extends through and is freely movable in aligned slots 31 and 32 of plate 11 and of a coin slide 33 movably mounted and guided between said plates 11 and 30 as shown clearly in Figure 3. It will be seen that the slot 32 extends rearwardly from a coin-receiving opening 34 of slide 33. The arrangement is such that a coin placed in opening 34 will engage arm 25 when slide 33 is pushed rearwardly or inwardly so as to swing gate 20 away from gate 19 and release the lowermost article so that it will be dispensed from the machine by passing downwardly through slot 12 and then being delivered outwardly of the casing through opening 14 into tray 15. At the same time, the arm 26 moves downwardly into engagement with the coin so as to positively and promptly eject said coin from the slide downwardly into a coin receptacle 35 provided in the bottom of casing 5 beneath the plate 11, the forward portion of slot 31 in plate 11 being sufficiently large to permit the downward passage of the coin therethrough. Obviously, as soon as the coin is ejected from the slide into the coin receptacle 35, the arm 25 is released so that the spring 27 may immediately return the gate 20 to its normal position where it cooperates with the gate 19 for receiving and sustaining the next succeeding article in position to be dispensed when the coin slide is again properly actuated with a second coin disposed in its opening 34. By varying the interval between the opening movement of gate 20 and the ejection of the coin from the slide 33, the number of articles dispensed at each operation may be varied within certain limits. With the arrangement shown, the arm 26 is arranged to eject the coin as soon as the gate 20 is opened, thereby permitting return movement of gate 20 in time to only permit the dispensing of one article at a time. The plate 11 has a forward extension 36 that projects through the front of the casing to support the outer end of slide 33, the front of casing 5 being provided with a narrow slot directly

25 above the extension 36 through which the slide 33 moves. As is usual in coin slides, the outer end of slide 33 has an upturned end or finger piece 37 to facilitate its manual actuation. It will of course be understood that the slide 33 may be manually returned to its outward position for exposing the opening 34 so that a coin may be placed within the latter.

30 The coin receptacle 35 may have its front and bottom walls constituted by portions of the front and bottom walls of casing 5, as shown, the bottom wall of the receptacle being hinged to the back wall of the casing as at 38 so that the coin receptacle may be swung downwardly and rearwardly to an open position when removal of the coins is desired. Any suitable form of key controlled means 39 may be provided for locking the coin receptacle in closed position as shown in Figure 3.

35 The arrangement of the coin-controlled mechanism for the dispensing means at one side of the hopper 6 and adjacent the bottom of the casing 5 leaves a considerable unused space within said casing beside hopper 6, and such space is preferably utilized as a match safe when the machine 25 is employed for vending cigars or cigarettes. Such match safe includes a hopper 40 suitably mounted in the casing beside hopper 6 and adapted to have a number of matches placed therein with the head ends facing the front of the casing 5. The lower portions of the side walls of hopper 40 are disposed in downwardly converging relation as indicated at 41 where they join at their lower edges with the sides of a forwardly and downwardly inclined trough 42 of a width slightly 35 greater than the diameter of a single match. The lower end of trough 42 registers with a small opening 43 in the front wall of casing 5, which opening 43 is also of a diameter slightly greater than that of the head of a single match so that 40 discharge of the matches is permitted only one at a time. Due to the inclined position of trough 42, the matches will gravitate toward the front of casing 5 and the lowermost match will ordinarily project through the opening 43 in position 45 to be grasped and removed. As each match is removed another match will immediately take its place with the head end thereof projecting slightly through the opening 43. However, should the matches become clogged in the trough 42, a slight jar of the casing will cause one of them to project properly for convenient removal.

50 In the operation of the coin-controlled dispensing means, the slide 33 is pulled outwardly to the position of Figure 5 and a coin is placed in the opening 34 of the slide, outward movement of said slide being suitably limited as is well known in the art. The slide is then pushed rearwardly or inwardly and when it reaches the full line position of Figure 3 the coin will have engaged the arm 25 so as to cause the gate 20 to swing away from gate 19 upon further inward movement of slide 33 from the full line position of Figure 3 to the dotted line position thereof. This effects release of the lowermost article 8 65 so that it may pass to the tray 15 by way of slot 12 and chute 13 and opening 14. As soon as the gate 20 is opened sufficiently to release the lowermost article, the opening 34 of slide 33 will have aligned with the enlarged portion of slot 31 and the arm 26 will have engaged the coin so as to cause it to be promptly ejected from the slide into the receptacle 35. As soon as the coin is ejected from the slide, the arm 25 is released so that the spring 27 may promptly return the gate 70

to its normal position to engage and sustain the next succeeding article in position to be dispensed upon the next succeeding operation of the coin-controlled means.

5 From the foregoing description it is believed that the construction and operation as well as the advantages of the present invention will be readily understood and appreciated by those skilled in the art. It will be particularly noted 10 that the construction is extremely compact, simple, durable and efficient. The coin-controlled mechanism embodies a minimum number of frail parts and is therefore unlikely to readily get out of order, although being capable of being quickly 15 and economically repaired if found necessary. Minor changes in the details of construction illustrated and described are contemplated within the scope of the invention as claimed.

What I claim as new is:

20 1. In a machine for vending cigars or like elongated articles, the combination of a casing, an article-holding magazine arranged in said casing and provided with a bottom discharge opening slightly longer and wider than the elongated 25 articles to be dispensed, a pair of gates mounted in the casing directly beneath the magazine and longitudinally of and at opposite sides of said bottom discharge opening to receive therebetween each article as it is discharged from the magazine, one of said gates being movable toward and away 30 from the other, yieldable means to move the movable gate toward the other gate to grip opposite sides of and support the discharged article in a position to be dispensed, and manually operable 35 means to move said movable gate away from said other gate in opposition to said yieldable means for releasing the article gripped and supported.

by said gates, said manually operable means comprising a slide device mounted beneath the gates and a depending member rigid with the movable gate and arranged in the path of the slide device for actuation by the latter to operate the movable gate and release the article supported in position to be dispensed.

2. In a machine for vending cigars or like elongated articles, the combination of a casing, 10 an article-holding magazine arranged in said casing and comprising a hopper having downwardly converging front and rear walls providing a bottom discharge opening slightly longer and wider than the elongated articles to be dispensed, 15 said hopper extending downwardly from the top of and to a point spaced from the bottom of the casing, said casing having a top cover openable to permit access to said hopper, a horizontal plate rigidly mounted in the casing and on which said hopper is sustained, said plate having a slot 20 registered with and conforming in size and shape to said bottom discharge opening of the hopper, a pair of gates mounted on the underside of said plate longitudinally of and at opposite sides of said slot to receive therebetween each article as 25 it is discharged from the magazine, one of said gates being movable toward and from the other, yieldable means to move said movable gate toward the other gate to grip opposite sides of and support the discharged article in a position to be dispensed, 30 and manually operable means including a slide device mounted beneath the gate and operatively associated with the movable gate for actuating the latter to release the article supported in position to be dispensed.

35 PHILIP CEDAR.
